(57) **CLAIM**

The ornamental design for a lung isolation catheter for equilibrium ventilation, as shown and described.

DESCRIPTION

FIG. 1 is a front elevational view of a lung isolation catheter for equilibrium ventilation showing my new design;

FIG. 2 is a rear elevational view thereof;

FIG. 3 is a left side view thereof;

FIG. 4 is an enlarged view taken from FIG. 3;

FIG. 5 is a right side view thereof;

FIG. 6 is a top plan view thereof;

FIG. 7 is a bottom plan view thereof;

FIG. 8 is an enlarged view taken from FIG. 7;

FIG. 9 is a perspective view thereof; and,

FIG. 10 is an enlarged view taken from FIG. 9.

In the drawings, the broken lines are for the purpose of illustrating environment only and form no part of the claimed design.

The dash-dot line shown in FIG. 9 indicating the enlarged portions of FIGS. 11-12 form no part of the claim design.
